United States Patent Office

Des. 215,970
Patented Nov. 11, 1969

215,970

SLIDE PROJECTOR

Gerald J. Frey, 745 E. Union St.,
Pasadena, Calif. 91101

Filed Jan. 22, 1969, Ser. No. 15,441

Term of patent 14 years

Int. Cl. D16—03

U.S. Cl. D61—1

Fig. 2

Fig.3

Fig.4

FIGURE 1 is a perspective view of a slide projector embodying my new design;

FIGURE 2 is a right side elevational view of the slide projector;

FIGURE 3 is a top plan view of the slide projector; and

FIGURE 4 is a rear elevational view of the slide projector.

I claim:

The ornamental design for a slide projector, as shown.
